UNITED STATES PATENT OFFICE.

SPENCER G. NEAL, OF NEW YORK, N. Y., ASSIGNOR TO AUTOMATIC STRAIGHT AIR BRAKE COMPANY, OF WILMINGTON, DELAWARE, A CORPORATION OF DELAWARE.

DIAPHRAGM STRUCTURE.

Application filed December 28, 1920, Serial No. 433,714. Renewed January 26, 1923.

To all whom it may concern:

Be it known that I, SPENCER G. NEAL, a citizen of the United States, and resident of the borough of Manhattan, city, county 5 and State of New York, have invented certain new and useful Improvements in Diaphragm Structures (Case No. 41), of which the following is a specification.

It has been found in the practical operation of diaphragms made in accordance with Patent No. 1,062,300 and used in air brake apparatus, that that portion of the diaphragm between the rigid supporting members and the central floating or pulsating 15 supporting members is unduly stressed by the air pressure. In diaphragm structures made and used in accordance with the mentioned patent there is a very slight unsupported portion of the diaphragm between the central supporting members and the rigid marginal supporting members and this unsupported portion is apt to be stretched or excessively stressed in the operation of the air brake apparatus.

25 It is the main object of this invention to provide a diaphragm structure in which the excessive stress of the unsupported part of the diaphragm will be eliminated. Diaphragm structures of the kind indicated herein must be very sensitive. Usually they are formed of one or more sheets of very thin 30 copper in order to secure the required sensitivity. It is quite unsatisfactory to strengthen the diaphragm by means of rigidly held strengthening sheets or members. Such a structure is not sensitive enough and 35 does not respond readily enough to variations in air pressures. In carrying out this invention I employ a freely floating reinforcing or sustaining ring which is arranged to bridge the gap between the rigid marginal supporting means and the floating or pulsating central supporting means. This floating ring is of sufficient width to give ample 40 bearing surface on both the marginal supporting means and the central supporting means; and the central supporting means is so constructed as to prevent undue lateral shifting of the sustaining ring. By this 45 means the sustaining ring is maintained accurately in position to at all times bridge the gap between the rigid and pulsating supports while at the same time offering no resistance to the pulsations of the diaphragm. It is 50 manifest, therefore, that the freely floating 55

sustaining ring will prevent any undue stretching of the diaphragm and at the same time it will not in any way interfere with the sensitive response of the diaphragm to variations in air pressures.

60 In the drawing, Fig. 1 is a transverse vertical sectional view of a diaphragm structure showing the diaphragm deflected by air pressure from the normal;

Fig. 2 a similar view showing the diaphragm structure in normal position;

Fig. 3 an enlarged sectional view of one side of the diaphragm and its supporting structure showing the diaphragm deflected by air pressure from normal position;

70 Fig. 4, a view similar to Fig. 3, showing the diaphragm in normal or neutral position; and

Fig. 5 a detail perspective view of the 75 sustaining ring.

75 In the use of diaphragms made in accordance with patent No. 1,062,300 and used in the air brake apparatus as exemplified by Patent No. 1,326,211 dated December 30, 1919, the diaphragm 1, preferably of thin sheet 80 copper of one or more layers, is supported around its marginal edges by rigid supports 2. These supports are usually a part of the structure of the air brake apparatus, which need not be more specifically described herein. This rigid marginal support of the diaphragm is formed with an inwardly flaring mouth 3, which of course is annular, and permits of a certain limited flexing of the 85 diaphragm, the walls of said mouth receiving and supporting the diaphragm when it is deflected from normal position as indicated in Fig. 1 of the drawing. The central portion of the diaphragm is clamped between two central supporting members 4 and 5, 90 said members being usually connected to an operative part of the apparatus as indicated in the said Patent No. 1,326,211, but which need not be illustrated or described herein. The supporting members 4 and 5 are only 95 slightly smaller in diameter than the space between the inner marginal edges of the stationary supports 2 so that there is only a slight unsupported part of the diaphragm 100 between the central and marginal supports thereof. Preferably the lower supporting member 5 is curved upwardly on its upper bearing surface, and the lower surface of the upper supporting member 4 is correspondingly curved, a slight outwardly flar- 105 110

ing channel being formed between said supporting members, the outer portion of said channel being slightly greater in width than the thickness of the diaphragm so that the 5 diaphragm may have a slight lateral movement in the outer portion of said channel. This is clearly illustrated in Fig. 3 of the drawing.

It has been found in the practical operation of air brake apparatus having diaphragms supported as shown in the drawings and as described herein, that the very small unsupported part of the diaphragm around the margin of the inner supporting 10 members is unduly stressed and stretched when air pressure is applied. To avoid this stress and stretching I insert a bridge 6 which extends across the said unsupported part of the diaphragm, a portion 15 of said bridge ring extending into the channel 7 between the two central supporting members and into the channel 3 formed between the two rigid marginal supporting members. The upwardly curved 20 part of the flange 5^a of the lower supporting member holds the bridge ring against sidewise shifting, and maintains the bridge ring accurately in position to bridge the 25 space between the reciprocating and rigid 30 supporting members. This bridge ring may be of any desired thickness to resist the air pressures employed in the apparatus, but it is preferably flexible enough to yield readily under the pressures employed, as indicated 35 in Figs. 1 and 3 of the drawing.

By providing a floating bridge ring the 40 sensitiveness of the diaphragm is not interfered with as the said ring is merely flexed by the air pressure and all tendency to 45 buckle when the diaphragm returns to normal or neutral position is avoided. It is manifest that if a strengthening layer were rigidly clamped between the marginal and central supports it would have a great stiffening effect on the diaphragm and would 50 materially interfere with its sensitiveness and prevent its ready response to variations in air pressure. By means of the floating ring the desired support may be provided for the diaphragm when it is deflected from the normal by air pressure while at the same time the diaphragm as a whole is not stiffened.

Another advantage of the floating bridge 55 ring is that should the diaphragm become broken or ruptured the ring will form a seal and prevent excessive leakage through the diaphragm. The bridge ring will form a seal because its inner and outer margins will 60 be closely pressed against the supports when air pressure is on the diaphragm, as shown clearly in Fig. 3 of the drawing. Air will leak through the ruptured or broken diaphragm only when the pressure is sufficient

to deflect the diaphragm and at that time 65 the bridge ring will be pressed into intimate contact with its supports and will then serve as a support for the diaphragm and as a means for sealing any break therein.

In the drawing only one bridge ring is 70 shown for the reason that the diaphragm structure illustrated is designed to receive air pressure on one side only. As illustrated the bridge ring is under the diaphragm and the air pressure is designed to 75 be placed only on the upper surface thereof.

What I claim is:

1. In a diaphragm structure the combination of a diaphragm, a rigid marginal support therefor, a movable central support, 80 and a freely floating bridge ring extending across the space between said supports and adapted to engage both of said supports when the diaphragm is deflected from its normal position.

2. In a diaphragm structure the combination of a diaphragm, an outer marginal support therefor having a channel to receive said diaphragm, a central support for said diaphragm having a channel to receive 90 said diaphragm, and a freely floating bridge ring extending across the space between the inner and outer supports for the diaphragm and entering the channels in said supports.

3. In a diaphragm structure the combination of a diaphragm, an outer marginal support therefor having a channel to receive said diaphragm, a central support for said diaphragm having a channel to receive said diaphragm, a freely floating bridge ring 100 extending across the space between the inner and outer supports for the diaphragm and entering the channels in said supports, and means for preventing the lateral shifting 105 of the bridge ring.

4. In a diaphragm structure the combination of a diaphragm, a rigid marginal support therefor, a movable central support, and a bridge-ring extending across the space between said supports and adapted to engage both of said supports when the diaphragm is deflected from its normal position, one margin of said diaphragm being 110 free.

5. In a diaphragm structure the combination of a diaphragm, a rigid marginal support therefor, a movable central support, a bridge-ring extending across the space between said supports and adapted to engage both of said supports when the diaphragm 120 is deflected from its normal position, one margin of said diaphragm being free, and means for preventing the lateral shifting of the bridge-ring.

In testimony whereof I hereunto affix my 125 signature.

SPENCER G. NEAL.
